UNITED STATES PATENT OFFICE.

WILLIAM RALPH CONCIE, OF SPOKANE, WASHINGTON.

KEY-FASTENING DEVICE.

1,104,106.

Specification of Letters Patent.

Patented July 21, 1914.

Application filed July 15, 1913. Serial No. 779,134.

To all whom it may concern:

Be it known that I, WILLIAM RALPH CONCIE, a citizen of the United States, residing at Spokane, in the county of Spokane and State of Washington, have invented new and useful Improvements in Key-Fastening Devices, of which the following is a specification.

My invention relates to an improved door lock attachment and has as its principal object the provision of a device which may be readily fitted to a door lock in order to make it impossible to pick the same.

A second object is to provide an attachment which shall be sufficiently cheap to warrant its use in connection with cheap locks to prevent them being picked.

A final object of my invention resides in the particular arrangement and combination of parts hereinafter described.

In the accompanying drawing:—Figure 1 is a plan view of a lock having my improved device attached thereto. Fig. 2 is a view similar to Fig. 1 with the mechanism so arranged that it is impossible to turn the key. Fig. 3 is a side elevation of the device in the position shown in Fig. 2. Fig. 4 is a section on the line 4—4 of Fig. 2. Fig. 5 is a detail perspective view of the operating member of my device. Fig. 6 is a view in side elevation of the operating mechanism before it has been assembled.

In the separate views the same part is designated by the same reference character.

Referring more particularly to the drawing, 1 is a plate which is fastened to the door 2 by means of screws such as 3—3. The plate 1 is provided with a bore 4 which is countersunk as shown at 5. I provide a spindle 6 which extends through the plate 1, said spindle being provided with a cross portion 7 and a collar 8 which are adapted to fit in the bore 4 and the countersunk portion 5 thereof, respectively. For use in connection with the spindle 6, I provide an eccentric 9 which is provided with a rim or collar 10 and connected to a sleeve 11 which has a nut 12 provided with a milled edge, said nut being at the end of said sleeve 11 opposite said eccentric. It will be seen also that the eccentric 9 is provided with a shoulder 13, the eccentric 9 and sleeve 11 and nut 12 being made in one piece and being provided with a bore 14 extending therethrough, the shoulder 13 surrounding one end of said bore. It will be understood

moreover, that the bore 14 is adapted to fit over the reduced end of the spindle 6. It will also be seen that the spindle 6 and sleeve 11 are provided with complementary holes 15 and 15' adapted to receive a screw 16 by which the two may be fastened together.

The locking portion proper is designated as 17 and comprise a shank 18, the upper portion of which is bent outwardly away from the face of the door as shown at 19 and, near its upper end, is provided with a pair of shoulders such as 20—20, the portion 18 being extended upwardly beyond the shoulders 20 to form a catch 21. At the end opposite the catch 21 the member 17 is enlarged to form a portion 22 which is provided with a slot 23 of the same diameter as the eccentric 9.

In assembling my device it will be understood that the spindle 6 is passed through the bore 4 in such a direction that the collar 8 fits in the countersunk portion 5. The end 22 of the locking member 17 is then passed over the spindle 6 and the eccentric 9 and sleeve 11 passed over the spindle 6 in such a manner that the collar 13 comes in contact with the end of the cross portion 7. The screw 16 is then screwed into the holes 15 and 15' whereupon the device is ready to be assembled on the door. It will be seen that when the parts have been assembled as just described, all of the parts are held firmly but rotatably to the plate 1 on account of the engagement between the plate 1 and the collar 8 on one side and between the plate and the eccentric 9 on the other side, while the member 17 is held by the collar 10 which projects beyond the edges of the slot 23, so as to hold the portion 22 against the outer face of the plate 1.

In using my device the key 25 is first turned so as to lock the door to which this lock is connected and the nut 12 is turned so that the major portion of the eccentric 9 is below the axis of the spindle 6. The member 17 is then turned up into the position shown in full lines in Fig. 2 whereupon the key is turned in the position shown in Fig. 1, the member 17 being of such length that it will just pass into the hole in the end of the key when the parts are in the position just mentioned. The key is then turned so that its handle is horizontal and the nut 12 is then turned so that the eccentric is brought up, and this forces the member 17 upwardly so that the end 21 projects

through the key. It will thus be seen that when the parts are in the position shown in Figs. 2 and 3, it will be absolutely impossible to turn the key by the use of nippers no matter how strong a person on the outside of the door may be, as the slightest movement to the left or right of the key handle will cause it to strike the shoulder 20 thus preventing further movement.

10 When it is wished to throw the device entirely out of operation, for instance during the day, the piece 22 may be swung into the position shown by the dotted lines in Fig. 1.

15 From the foregoing it will be seen that I have provided a cheap and efficient device which is adapted to be used in connection with the ordinary spring lock and which will absolutely prevent them from being 20 picked.

It will be understood also that while I have shown and described the preferred form of my invention, various modifications thereof may be made without departing 25 from the spirit of my invention and that I contemplate all such modifications as are mechanically equivalent to the arrangement shown and described herein. In particular, it should be understood that in place of the 30 specific locking member 17 shown and described herein, I may substitute therefor a ring member surrounding the eccentric 9 and having two spring wires extending upwardly therefrom and bent outwardly at 35 their upper ends so that the equivalent of the locking shoulders 20 shall be formed above the key handle instead of below it.

Having thus described my invention, what I claim is:—

40 1. A key fastening device comprising in combination, a plate adapted to be fastened to a door and provided with a countersunk bore therethrough, a spindle inserted in said bore and provided with a shoulder occupying 45 said countersunk portion, said spindle projecting beyond the face of said plate opposite said countersunk portion, an apertured eccentric fastened to said spindle where it projects from the face of said plate, 50 and a key fastening member rotatively engaging said eccentric.

2. A key fastening device comprising in combination, a plate adapted to be fastened to a door and having a bore therethrough 55 countersunk at one side thereof, a spindle inserted in said bore having a flange or collar occupying said countersunk portion, said spindle projecting from the face of said plate opposite said countersunk portion, an 60 integral structure rigidly attached to said spindle comprising an apertured eccentric and sleeve, said eccentric having a collar,

and a key fastening member relatively engaging said eccentric intermediate said plate and said collar.

3. A key fastening device comprising in combination, a plate adapted to be fastened to a door and provided with a countersunk bore therethrough, a spindle inserted in said bore and provided with a shoulder occupying 65 said countersunk portion, said spindle projecting beyond the face of said plate opposite said countersunk portion, an apertured eccentric fastened to said spindle where it projects from the face of said plate, 70 a key fastening member rotatively engaging said eccentric, said eccentric being provided with a collar engaging the outer surface of said key fastening element and holding the same against the outer face of said plate.

4. A key fastening device comprising in combination, a plate adapted to be fastened to a door provided with a countersunk bore therethrough, a spindle inserted in said bore and having a collar occupying the countersunk bore, said spindle projecting beyond the face of said plate on the side opposite the countersunk bore, a key fastening element placed over said spindle and provided with an elongated slot therein, and an operating 85 structure attached to the projecting portion of said spindle, said structure comprising an eccentric having a diameter equal to the width of said slot and inserted therein, a sleeve rigid with said eccentric, and a nut 90 rigid with said sleeve, said eccentric and sleeve being perforated to receive the projecting portion of said spindle, said eccentric having a collar of greater diameter than the slot in said fastening element, said collar projecting over the face of said element and holding said element against the face 95 of said plate.

5. A device of the class described comprising in combination, a member adapted to engage a key to prevent the same from turning, and a member adapted to throw said first mentioned member into locking position, said first mentioned member having pivotal engagement with said second mentioned member.

6. A device of the class described comprising in combination, a member adapted to engage a key to prevent the same from being turned, and a rotatively mounted eccentric for operating said member, said member being pivotally connected to said eccentric.

In testimony whereof I affix my signature in the presence of two witnesses.

WILLIAM RALPH CONCIE.
